UNITED STATES PATENT OFFICE.

ERNEST R. BURKEY, OF CLEVELAND, OHIO.

PAPER-HANGING DEVICE FOR WALLS.

Application filed May 16, 1925. Serial No. 30,647.

The present invention relates to a device for hanging wall paper, and has for its object to provide a device of this character which embodies novel features of construction, whereby wall paper of the usual or very wide widths can be quickly and accurately applied to the side walls of a room.

Further objects of the invention are to provide a device of this character which is 10 comparatively simple and inexpensive in its construction, which can be quickly manipulated and adjusted to hold the paper in proper position for application to the side wall and obtain a perfect match with the 15 wall paper which was previously applied, and which will enable strips of great width to be hung without difficulty.

One particular embodiment of the invention is shown and described in detail for 20 illustrative purposes, although it will be understood that many modifications and changes can be made in the details of construction without departing from the spirit of the invention.

25 For a full understanding of the invention reference is to be had to the following description and accompanying drawings, in which,

Figure 1 is a side elevation of a paper 30 hanging device which is constructed in accordance with the invention, showing the same in operative position for applying a strip of paper to a side room.

Figure 2 is a top plan view thereof.

35 Figure 3 is an enlarged transverse sectional view through the paper supporting cross bar, showing the manner in which the same is supported on the balancing pin of the main frame.

40 Figure 4 is an enlarged transverse sectional view on the line 4-4 of Figure 1, showing the rack and pinion arrangement for adjusting the height of the standard.

45 Corresponding and like parts are referred to in the following description and indicated on all of the views of the drawings by like reference characters.

50 Referring to the drawings, the reference character A designates a standard which is provided at its lower end with a base B, said base being adapted to rest upon the floor or a platform and to support the standard in an upright position. The lower face of the base may, if desired, be covered with

felt or similar material so that it will not 55 mar or scratch a floor or other surface upon which it may be placed. An inclined arm C projects laterally from the upper end of the standard and is adapted to support a cross bar D to which the paper or material 60 E to be applied to the side wall is attached.

The standard A comprises a lower tubular section 1 and an upper section 2 which telescopes therein. The section 2 is provided at one side thereof with a rack 3 which slides 65 within a channel 4 at one side of the lower standard section 1, thereby preventing relative rotation of the two standard sections. A pinion 5 engages the rack 3, being rigid with a short shaft 6 which is journaled upon 70 the lower section 1 of the standard and has a handle 7 at one end thereof. With this construction it will be obvious that by manipulating the handle the pinion can be turned to raise or lower the upper section 2 75 of the standard and adjust the height of the standard as may be desired. The frictional engagement between the parts is such as to hold them in an adjusted position and render a special locking device unnecessary. 80

A collar 8 is rigidly applied to the upper end of the standard and the inner end of the inclined lateral arm C is rotatably mounted upon the collar so that the lateral arm can be swung around about the standard 85 as a center, although the frictional engagement between the parts is sufficient to avoid looseness and prevent unnecessary play of the parts.

The lateral arm C comprises an inner 90 tubular section 9 and an outer rod section 10 which telescopes within the tubular section 9. The rod is formed with a rack 11 which is engaged by a pinion for moving the rod in and out, the pinion shaft terminating in 95 a handle 12 which can be conveniently manipulated for lengthening or shortening the lateral arm as desired.

The cross bar D may be of any desired 100 length, depending upon the width of the paper or other material to be hung. One end of the paper E is folded around the top of the cross bar D and engaged by spring clips 13 with which the cross bar is provided. The back of the cross bar is provided at substantially its central portion 105 with a recess 14 which loosely receives a balancing pin 15 projecting from the end of

the lateral arm C. The cross bar is free to swing upon the balancing pin, and the paper E which is secured to the cross bar is thereby permitted to hang in a vertical 5 position.

When using the device the paper E or other material which it is desired to apply to the wall is pasted on the back thereof in the usual manner, after which one end of 10 the paper is secured to the cross bar D by means of the spring clips 13. The paper may be folded in the usual manner while it is being preliminarily handled and applied to the device. After the paper has been attached to the cross bar D the latter is applied to the balancing pin 15 of the lateral arm. The paper then hangs vertically and the lower end thereof may be unfolded, if it was previously folded. The height of the 15 standard is adjusted approximately to the height of the room, and the handle 12 may be manipulated to slide the rod 10 of the lateral arm outwardly. Owing to the inclination of the lateral arm the cross bar at 20 the outer end thereof is moved upwardly at the same time that it is moved outwardly and the cross bar may thus be fitted readily in the angular space between the ceiling and the side wall. The paper or other material to be hung is thus moved close to the 25 side wall, and the handle 7 can then be manipulated to raise or lower the paper slightly as may be necessary to obtain an accurate match of the pattern on the strip being hung with the pattern on the strip previously hung. The paper is thus suspended in 30 proper position close to the side wall, and the operator then applies his smoothing brush to the paper and brushes it against the wall. This operation can be repeated for 35 the successive strips of paper or other material which are applied to the side wall. In using the device openings can be cut out roughly from the strip while it is suspended 40 from the paper hanging device and before it is pressed on the wall, thereby avoiding the possibility of smearing woodwork or other similar parts with paste. The paper is suspended by the device so that the operator 45 has both hands free and can devote his attention to obtaining a perfect match and cutting out portions as may be desired. This device not only provides for quickly and 50 expeditiously hanging the paper, but simplifies the operation so that an unskilled person can do a perfect job of hanging paper 55 on the side walls of a room. While the device has been described as used for hanging paper it may be mentioned that it can 60 also be used to advantage for holding stencils, and will hold the stencils in position with greater security than they can be held by a plank or other customary supporting means.

65 Having thus described my invention what

I claim as new and desire to secure by Letters Patent is,

1. A device for applying paper to a side wall, including a standard adapted to rest upon the floor, a lateral arm pivotally mounted upon the standard to swing in a horizontal direction, a cross bar arranged at substantially right angles to and pivotally mounted upon the end of the lateral arm to swing freely into different angular positions, and means for securing an end of a strip of wall covering to the cross bar whereby it can be supported in close proximity to the wall and will hang vertically by gravity. 80

2. A device for applying a strip of wall covering to a side wall, including a standard adapted to rest upon the floor, means for adjusting the height of the standard, a lateral arm projecting from the standard, means for adjusting the length of the lateral arm, a cross bar pivotally mounted upon the end of the lateral arm at substantially right angles thereto so that it can swing into different angular positions, and means for securing a strip of wall covering to the cross bar whereby the wall covering can be supported in close proximity to the wall and will hang vertically by gravity. 90

3. A device for applying wall covering to a side wall, including a standard adapted to rest upon the floor and formed in telescoping sections, means for manipulating the sections to lengthen or shorten the standard, a lateral arm projecting from the standard and formed in telescoping sections, means for manipulating the telescoping sections to lengthen or shorten the arm, a cross bar carried by the end of the arm at substantially right angles thereto and adapted to be adjusted to assume a position close to the side wall and at the top thereof, and means for securing a strip of wall covering to the cross bar so that it will hang therefrom in close proximity to the side wall. 110

4. A device for applying wall covering to a side wall, including a standard adapted to rest upon the floor, a lateral arm inclined upwardly from the standard and pivotally mounted upon the standard to swing horizontally, said lateral arm being formed in telescoping sections, means for adjusting the sections to shorten or lengthen the arm, a cross bar carried by the end of the arm and adapted to be adjusted to bring it close to the side wall at the top thereof, and means for securing a strip of wall covering to the cross bar whereby the wall covering will hang therefrom in close proximity to the side wall. 115

5. A paper hanging device including a supporting frame, a balancing pin thereon, a cross bar loosely engaged by the pin, and means for securing a wall covering to the cross bar. 120

6. A paper hanging device including a supporting frame, a balancing pin projecting therefrom, a cross bar provided with a recess loosely receiving the balancing pin, and means on the cross bar for engaging a strip of wall covering.
7. A device for applying wall covering to a side wall, comprising a supporting frame adapted to rest upon the floor, a cross bar, a balancing pin for detachably and loosely mounting the cross bar on the frame, and means for securing a strip of wall covering to the cross bar whereby it can be supported in close proximity to the wall, the balanced
- mounting of the cross bar enabling the wall covering to hang vertically by gravity.
8. A paper hanging device including a standard formed in telescoping sections, means for manipulating the sections to lengthen or shorten the standard, a collar on the standard, an extensible lateral arm pivotally mounted upon the collar and adapted to swing around the standard as a center, a cross bar mounted upon the lateral arm, and means for securing a strip of wall covering to the cross arm.

In testimony whereof I affix my signature.
ERNEST R. BURKEY.
